12 Claims. (Cl. 102—39)

The present invention relates to an ignition device, and more particularly to long-burning ignition means for gas mixtures, especially in combustion engines.

Under certain prerequisites and operating conditions gas mixtures containing air or oxygen can be ignited only by means of a hot ignition flame burning over a longer period of time. This is the case, for example, with certain power engines or motors operated with gaseous propellants. One has utilized heretofore for such purposes so-called ignition lighters which are ignited outside of the engine or motor and ignite the propellant mixture after insertion through an aperture into the interior of the motor or engine. Aside from the resulting complicated handling of such prior art ignition lighters, one has to accept the disadvantage that strong residues may occur which act in a corrosive manner on the engine or engine parts, especially in the presence of chlorine or sulphur-containing residues.

Disadvantages of this type are avoided by the present invention in that the ignition flame is produced by burning down a hollow cylinder of powder accommodated in a cartridge case and essentially consisting of components non-dangerous to corrosion, which is caused to burn down in the direction from the cartridge case end by the ignition jet penetrating through the cylinder channel and produced by an ignition means arranged in the bottom piece of the cartridge. A cartridge of this type can be ignited externally by an extremely simple striker mechanism having a striker pin or by an electric fuse or primer. Corrosion-dangerous residues do not occur with such an arrangement; for insofar as the ignition means contains any corrosion-dangerous components at all, they represent only a minimum fraction of the corresponding residues of a prior art ignition lighter.

The ignition composition of the ignition device is so mixed and compounded according to a further feature of the present invention that it does not produce during penetration through the hollow cylinder the heat required for the ignition of the powder. Instead, one of several foils are placed over the hollow cylinder of powder which are ignited by the ignition jet and which only in their turn cause ignition of the powder composition.

With several powder foils disposed adjacent one another, the innermost foil is appropriately notched, grooved, or perforated and the rims of the apertures or perforations are bent inwardly so that the ignition by means of the ignition jet becomes particularly safe. The powder foils or sheets in general will be at a distance of 30 to 70 mm. from the primer or fuse.

The ignition composition and powder foils are made appropriately of the same powder mass. Particularly favorable for such mass is a mixture of nitrocellulose and nitroglycerine and/or nitroglycol. This mixture can be readily manufactured and handled.

In one test with a blank of about 30 mm. in length, an external diameter of 16 mm. and an internal diameter of 6 mm., a burning duration of 22 to 30 seconds was achieved with the present invention. By increasing the length of the powder body, the burning duration may be correspondingly increased. The burning duration is constant with sufficient certainty. If one desires to reinforce the flame, then the outer diameter of the blank will be

2

increased with the same inner diameter. The burning duration may also be correspondingly reduced by shortening the length of the blank.

Accordingly, it is an object of the present invention to provide an ignition device for gas mixtures which obviates the aforementioned short-comings and drawbacks encountered by the prior art constructions by extremely simple means.

Another object of the present invention resides in the provision of ignition means for gas mixtures which assure with reliable certainty a given burning duration over relatively long period of time.

A further object of the present invention resides in the provision of an ignition device, especially for engines operating with propellants consisting of gas mixtures that permit simple handling during the ignition of such engines.

Still another object of the present invention resides in the provision of an ignition device for igniting gas mixtures, especially in power engines, which minimizes the danger of corrosion producing residues.

Still another object of the present invention resides in the provision of an ignition device of the type described above which is not only extraordinarily safe and reliable in operation but also permits the use of powder mixtures that can be readily manufactured and handled.

A further object of the present invention resides in the provision of an ignition means for gas mixtures of engines which is relatively simple in structure, inexpensive in manufacture and constant in its burning duration.

These and other objects, features, and advantages of the present invention will become more obvious from the following description when taken in connection with the accompanying drawing which shows, for purposes of illustration only, one embodiment in accordance with the present invention, and in which the single figure thereof is a cross-sectional view through one embodiment in accordance with the present invention.

Referring now to the single figure of the drawing, the ignition device in accordance with the present invention has about the shape of a sporting cartridge with a case 1 and a bottom piece 5. In the embodiment it is assumed that the case 1 is made in one piece with the bottom piece 5, especially of conventional plastic material. A primer or fuse 2 of conventional construction is inserted into the bottom piece 5. The burning charge 3 is constituted by a blank provided with a free internal channel 6. A number of powder foils or sheets 4 are placed over the blank 3 which are held in place by the flanged-over rim 7 of the case 1. The foils 4 are apertured and the aperture rims are bent inwardly at 8.

While we have shown and described one embodiment in accordance with the present invention, it is understood that the same is not limited thereto but is susceptible of numerous changes and modifications as known to a person skilled in the art and we therefore do not wish to be limited by the details shown and described herein but intend to cover all such changes and modifications as are encompassed by the scope of the appended claims.

We claim:

1. A cartridge for igniting gas mixtures with air or oxygen requiring a hot ignition flame burning for a relatively long period of time, especially for gaseous propellants of engines, comprising a generally tubular case having rearward and forward ends; a bottom piece substantially closing the rearward end of said case; a generally tubular burning charge within said case forming a generally axially extending firing channel substantially void of propellant charge; means at the forward end of said case adjacent to said charge for igniting said burning charge including at least one sheet of ignition powder extending generally transverse to the axis of said channel; said sheet being provided with at least one aperture aligned with

said channel; the area of the cross section of said aperture being substantially less than the area of the cross section of said channel; sheet means adjacent said apertured sheet for completely closing said aperture and said channel; and said sheet and sheet means being the sole end closure for said cartridge case.

2. The cartridge according to claim 1, wherein said sheet adjacent said aperture is bent substantially rearwardly into said channel progressively toward the cartridge axis.

3. The cartridge according to claim 2, including additional apertured sheets of ignition powder substantially identical to and in axially stacked engagement with said first-mentioned apertured sheet.

4. The cartridge according to claim 3 wherein each of said apertured sheet is substantially foil-like; said case and said bottom piece being homogeneously constructed of plastic; the forward portion of said case being provided with an inwardly directed substantially annular flange; said flange directly engaging said sheet means and tightly pressing said sheets into direct engagement with the forward portion of said burning charge; primer means within said bottom piece aligned with said channel for projecting an ignition flame through said channel and directly onto said sheets for igniting said sheets prior to the ignition of said charge; said burning charge consisting essentially of nitrocellulose and one or more of the substances selected from the group consisting of nitroglycerol and nitroglycerine; said burning charge having a residue that is substantially non-corrosive.

5. The cartridge according to claim 1 including additional apertured sheets of ignition powder substantially identical to and in axially stacked engagement with said first-mentioned apertured sheet.

6. The cartridge according to claim 5, wherein said apertured sheet is substantially foil-like.

7. The cartridge according to claim 5, wherein said burning charge consists essentially of nitrocellulose and at least one of the compounds selected from the group con-

sisting of nitroglycerine and nitroglycol; said burning charge having a substantially non-corrosive residue.

8. The cartridge according to claim 1, wherein each of said apertured sheet and sheet means is constructed as a foil.

9. The cartridge according to claim 8, wherein said sheet adjacent said aperture is bent substantially rearwardly into said channel progressively toward the cartridge axis.

10. The cartridge according to claim 8, wherein said burning charge consists essentially of nitrocellulose and at least one of the compounds selected from the group consisting of nitroglycerine and nitroglycol; said burning charge having a substantially non-corrosive residue.

11. The cartridge according to claim 1, wherein said burning charge consists essentially of nitrocellulose and at least one of the compounds selected from the group consisting of nitroglycerine and nitroglycol, said burning charge having a substantially non-corrosive residue.

12. The cartridge according to claim 11, wherein said sheet adjacent said aperture is bent substantially rearwardly into said channel progressively toward the cartridge axis.
